APPARATUS FOR LOCATING LIDS ON CANS

Frank Oscar Levi Chorlton, Bury, England

Application July 24, 1933, Serial No. 681,996
In Great Britain August 10, 1932

11 Claims. (Cl. 113—18)

This invention relates to an improved apparatus for locating lids on containers by clenching preparatorily to final closure by a seaming machine, and is especially applicable to those cases where the charged containers are subject to a vacuum process before or whilst seaming when, unless the lid is preparatorily held in proper position by clenching, it is likely to be displaced in the act of seaming. The clenching is effected by turning over, at two or more (preferably three) places, the rim of the lid over the flared mouth of the container, the local turning-over being such as to form a smooth and continuous part of the complete seaming by which the final closure is made. The clenching apparatus may be combined with the seaming machine in which the lids are fed from a magazine to the positioned containers, or may be adapted to clench the lids prior to the containers being passed to the seaming machine, in which case the lids may be positioned on the container by hand, or be fed automatically thereto from a magazine by the operation of the clenching machine, or by separate hand operated release means.

The preferred form and modifications are illustrated in the accompanying drawings, in which:

Figs. 1, 1A and 2 show a form of clenching apparatus adapted to be combined with a seaming machine; Fig. 1 being an elevation in medial section; Fig. 1A a fragmentary section on the line IA, IA of Fig. 2; and Fig. 2 a plan in section on the line II, II of Fig. 1.

Fig. 3 is an elevation of the general arrangement, where the clenching apparatus is combined with a seaming machine, and shows the mode in which the clenching apparatus is actuated from the cam shaft of the seaming machine.

Fig. 4 is a plan view of a modification of Fig. 3.

Fig. 5 is a fragmentary plan and shows a modification of the arrangement of Figs. 1 and 2.

Figs. 6, 6A, 6B and 6C are fragmentary elevations, and illustrate the mode of operation of the arrangement illustrated in Figs. 1 and 2.

Fig. 7 is a plan view of a container and lid with the latter clenched in position.

Figs. 8 to 10 illustrate a modification of the invention suitable for use when it is desired to clench the lids in position on the containers before passing the latter to a separate seaming machine.

Fig. 8 is an elevation in medial section, and shows a clenching machine in which the lids are applied to the containers, and the latter located in the clenching position, by hand.

Fig. 9 is an elevation, in medial section, and shows a clenching machine provided with a magazine to hold a stack of lids, and

Fig. 10 is a fragmentary plan view of suitable means of successively releasing the lids in the arrangement illustrated in Fig. 9.

Fig. 11 shows a clenching machine having a magazine in which the lids are stacked, and in which the lids are released and clenched by means similar to those illustrated in Figs. 1 and 2.

Referring first to Figs. 1, 2 and 3:

1 is a flanged ring termed the main ring which is attached by lugs 2 to a bracket 3 secured to the part 4 of the main frame of the seaming machine A. The bore of the ring forms a magazine adapted to hold a stack of lids B, and may be provided with vertical rods 5 to form an extension of the magazine. A ring 6, termed the carrier ring, is fitted to the outer surface of the cylindrical part of the main ring 1, and is adapted to slide on the main ring, but is prevented from rotation relatively to the latter by any suitable means, for example by a key 1a fitted to the ring 1 and a keyway 6a in the ring 6.

The clenching members 7 and supporting members 8 are carried from the flange 6b formed at the lower end of the carrier ring 6. There are at least two clenching and two supporting members; preferably three are fitted and alternately disposed as shown. Each clenching member is attached to the flange 6b of the carrier ring so as to be capable of sliding thereon in a direction approximately radial to the central axis x, x, with which the axis of the container C aligns when it is positioned for clenching. The sliding attachment may conveniently be made by beveling the edges of the members 7 and 8 and providing the usual V guides in the flange 6b of the carrier ring 6, as shown in Fig. 1A.

The members 7 and 8 are provided with respective actuating studs 9 and 9¹, the screwed lower ends 9a of which are screwed into and riveted over tapped holes in the said members; the body parts 9b of the studs pass through and may be a sliding fit in slots 6d in the flange 6b, and the studs 9 and 9¹ carry at their upper ends rollers 9c and 9¹c, which rollers fit cam slots formed in the flange 10a of a ring 10 the bore of which fits the outer cylindrical part of the carrier ring 6. The ring 10, which will be termed the actuating ring, has a locating flange 10b and it is held against axial movement relatively to the main ring 1 by means of the recessed split sleeve 1b which is bolted to the flange 1c of the main ring 1.

55

The members 7 and 8 are preferably uniformly spaced round the axis x , x , and are alternately disposed. The rollers 9c of the studs 9 fitted to the clenching members fit cam slots 13 formed in the flange 10a, and the rollers 9c' of the studs 9' fitted to the supporting members 8 fit cam slots 14 in the said flange. Pins 15 or pins and rollers are fixed to the actuating ring 10 and these fit in circumferential cam slots 6c formed in the cylindrical part of the carrier ring 6.

It will be seen from an inspection of the shape of the cam slots 13 and 14, that if angular movement in the direction of the arrow y be imparted to the actuating ring 10, the cam slots 12, acting through the rollers 9c and studs 9 attached to the clenching member 7, will cause the latter to move radially outwardly from the positions in which they are shown and the cam slots 14 acting through the rollers 9c' and studs 9' attached to the supporting members 8 will cause the latter to move radially inwardly from the positions in which they are shown, and that angular movement imparted to the actuating ring 10 in a direction opposite to that of the arrow y will in like manner impart inward radial movement to the members 7 and outward radial movement to the members 8.

Angular movement may be imparted to the actuating ring in any convenient manner; in Figs. 1, 2 and 3, a section of the periphery of the actuating ring is provided with teeth 10c, with which are engaged by the teeth 16a of a toothed section 16b formed at the end of a lever 16 pivoted on the stud 16c fixed to the part 4 of the frame of the seaming machine A. A lever 16d (see Fig. 3) is made integral with the lever 16, and is connected by a rod 16c to a lever 16f mounted on a stud 16p and a toothed segment 16g the teeth of which mesh with rack teeth 16h of a bar 16k slidable in the bracket 16j attached to the main frame of the seaming machine A. $a1$ is the main cam shaft of the seaming machine, and the cam $a2$ thereon engages a cam roller 16m on the bar 16k. The cam $a2$ is so shaped and timed that when a container C is by any suitable transfer means positioned on the table $a3$, the actuating ring 10 had angular movement imparted to it which causes, in the manner hereinafter described, the release of the lower-most lid from the magazine and effects the clenching of the lid on the container, which is then passed to the seaming mechanism of the machine A.

Fig. 4 shows a modified arrangement for imparting angular movement to the operating ring 6; the ring 6 is provided with a lug 17 to which is pivoted one end of the lever 11a pivoted at 17b on which is pivotally mounted a radius rod 17c, which is in turn pivoted at 17d to the main arm a of the seaming machine. The short arm of the lever 11a is connected by a link 11e to the cam operated bar 11f slidably supported in the bracket 11g provided on its inner end with the cam wheel 11h through which to-and-fro movement is imparted to the bar 11f by the cam $a2$ mounted on the main cam shaft $a1$ of the beading machine, the shape and timing of the cam being arranged to impart, through the lever 11a, angular movement to the ring 6 so that the clenching operation is performed in co-ordination with the operation of the seaming machine.

Instead of slidably mounting the clenching members 7 and the supporting members 8 as described in connection with Figs. 1 to 3 they may

be constructed as pivoted levers 7a, 8a, as shown in Fig. 5; the levers 7a, and 8a being pivotally mounted on the ring 6 by pivot pins, 18 and 18'; the movement of the operating faces of the members 7a and 8a about the pivot pins 18 and 18' approximating to radial movement in respect to the axis x , x .

Movement is imparted to the members 7a and 8a by cam rollers 9d and 9d' carried on studs 9e and 9e', the said rollers and studs being equivalent to the rollers and studs of Figs. 1 and 2, the rollers 9d of the clenching members working in slots 13 formed in the actuating member 10 (see Fig. 1) and the rollers 9d' of the supporting members 8a working in slots 14 formed in the said member 10 to which angular movement is imparted as described in connection with Figs. 1 to 3 or Fig. 4.

The shape of the operating face of the clenching and supporting members is shown in Fig. 6 (see also Figs. 6A, 6B, and 6C showing the mode of operation). The face of the clenching member 7 is transversely undercut as at 7c so that when the clenching member reaches the inner limit of its stroke as shown in Fig. 6c it clenches a tangential portion $b1$ of the lid B so that the said portion engages with the flared end $c1$ of the container C.

The upper portion of the inner edge of the clenching member is bevelled off as shown at 7d for a purpose to be hereafter described. The upper portion of the inner face of the supporting member 8 is cut away transversely to form a transverse lip 8c. The three lips 8c of the three supporting members 8 normally engage the underside of the lowermost lid of the stack of lids and so support the stack in the magazine, as shown in Fig. 6 (in which, of course, one lip 8c only is shown). When the clenching stroke is made the lips 8c recede from under the lowermost lid and at the same time the bevelled edges 7d of the three clenching members are inserted between the lowermost lid and the next succeeding lid of the stack in the magazine (see Fig. 6A).

When the lowermost lid is free from the supports 8c it drops into position on the container C (see Fig. 6b), the stack of lids being in the meantime supported by the inclined surface 7d of the three clenching members.

Prior to the actual clenching movement, shown in Fig. 6C as having been accomplished, a pin 15 on the clenching member 10 (see Figs. 1 and 2) engages in the slots 6e on the carrier member 6 with the result that the member 6 and the parts carried thereby are given a downward movement, as a result of which the lid B is pressed onto the container C by the under-side 7e of the clenching members; thus ensuring a satisfactory clenching attachment.

Referring to the mechanism as attached to a seaming machine the method of working is as follows:—A container having been placed or brought centrally beneath the mechanism in correct sequence with the general working of the machine the movement of the actuating ring 10 causes the supporting members 8 to retract outwardly and allows the lowest lid of the stack to drop in place upon the container. At the same time the clenching members 7 advance inwardly so as to enter between this lid and the next lowest in the stack, so supporting the stack. Further movement of the ring 10 causes the ring 6 to descend, pressing the lid on the container by the members 7 and at the same time advancing them inwards so as to curl or lip the edge over the flanged 75

top of the container, securing the lid in place. Movement of the ring 10 in the reverse direction then takes place, retracting the member 7, lifting the ring and advancing the members 8 to receive and carry the stack of lids which the withdrawal of the support the members 7 has allowed to drop. The container is then removed and another takes its place, when the cycle is repeated.

When used in conjunction with automatic container feeding a trigger controlled gear of any well known form may be embodied in the gear connecting the mechanism to the source of motion in such a manner that the mechanism only operates on the movement of the trigger by the approaching container.

The modification of the invention above described is suitable for incorporation with a seaming machine, but as stated, the invention is equally applicable to those cases in which a separate hand operated clenching machine is employed to locate the lids in position on the containers before the containers are passed to a process plant or to a seaming machine.

Figs. 8 to 11 illustrate suitable forms of hand operated clenching machines constructed in accordance with the invention.

Referring first to Figs. 8 and 9.—20 is a bracket or main arm of the machine, suitable for attachment to a table or other supporting means 22. 30 21 is a ring frame bolted to the bracket 20. 23 is a plate carried by the ring frame 21, said plate having a centrally screwed bore into which the upper end of the main ring 24 is screwed, the ring 24 serving to carry the clenching members 17, the operating faces of which are constructed as described in connection with the member 7 of Figs. 1 and 2.

The members 17 are operated by means of pins 26 attached thereto, which pins enter cam slots in the actuating ring 27, which is mounted upon the externally cylindrical portion of the ring 24 and is secured in position and held against axial movement by the split sleeve 30.

Angular movement is imparted to the actuating ring 27 by providing a sector-like portion of its periphery with teeth 27a with which engage teeth 29a formed on the quadrant portion 29b of a bell crank lever 29c fulcrumed on a stud 29 carried by the main frame 21 and angular movement is imparted to the ring 27 by the operating handle of the bell-crank lever 29c.

The container C with the lid in position thereon is located by hand centrally in respect to the ring 27 and clenching members 17 when the latter are in their retracted position. The handle of the bell-crank lever 29c is then actuated, causing the rotation of the ring 27 and the cam slots therein, which slots by engaging pins 26 cause the clenching members 17, of which there may be two or three, (two only being shown in Fig. 8), to make their inward or clenching stroke.

The container with the clenched lid retained in position is removed and is replaced by a container with the lid in position thereon, and the action repeated.

In Fig. 9 the construction and action in regard to the clenching is as described in connection with Fig. 8.

In Fig. 9, however, pins 31 are fitted to form a magazine to contain a stack of lids and the mechanism illustrated in Fig. 10 is fitted to enable the lowermost lid to be released so as to fall into position on the container prior to the clenching action.

The releasing mechanism comprises two

quadrantal levers 32 and 33 pivoted by the pins 34 and 35 to the ring 23. The two quadrantal levers 32 and 33 are connected together by a link 37, and the quadrantal lever 33 has a handle 36 made integral therewith. Each of the levers 32 and 33 has two projecting teeth 38 and 39. In the position shown in Fig. 10 the lowermost lid of the stack of lids in the magazine is supported by the oppositely located teeth 39. The movement of the handle 36 in the direction of the arrow w causes teeth 39 to be moved outwardly and release the lowermost lid in the stack, the teeth 38 moving inwardly in time to engage the lid next above the lowermost lid, and to support the stack.

When the lid thus released has been clenched on the container by the operation of the handle 29c, and another container has been placed in position, the handle 36 is moved in a direction opposite to the arrow w, to the position shown in Fig. 10, the teeth 38 release the lowermost lid, the teeth 39 moving inwardly to engage the lid next above the lowermost. The fitting of the lids and the clenching of them in position being thus effected by the alternate operation of the handles 29c and 36.

Fig. 11 shows a hand operated machine provided with a mechanism to hold a stack of lids, and in which the release of the lowermost lid, prior to the act of clenching, is effected by the combined action of clenching members 1g and supporting member 8g, in the manner described in connection with Figs. 1 and 2.

With regard to the frame 20 and supporting bracket 21, the construction is similar to that described in Figs. 8 and 9. The main ring 40 is supported from the ring 21, and on a cylindrical part of this ring a carrier ring 42 is fitted by which the clenching members and supporting members are slidably carried as described.

The pins 42a by which these members are actuated engage cam slots formed in an actuating ring 42 similar in construction to the actuating ring 10 (Figs. 1 and 2) and is held in fixed axial position in relation to the ring 40 by a split ring 43.

A portion of the periphery of the actuating ring 42 is fitted with teeth 44 with which engage teeth 45 formed on the quadrant portion 45 of the bell-crank lever 46, 48, mounted on a stud 47, to which lever angular movement is imparted by hand.

With the exception that the pins 42a are shown integral with respect to the clenching and supporting members, that these pins are actuated directly by the cam slots, and that angular movement is imparted to the actuating ring 42 by hand through the bell crank lever 46, 48, the construction and action of the arrangement of Fig. 11 are similar to those described in connection with Figs. 1 and 2.

In the modifications illustrated the container has been assumed to be a cylindrical container with a circular lid; the invention is, however, equally applicable to containers the cross-section of which and the shape of the lids of which are other than circular, the shape of the magazine being modified accordingly.

Having now fully described my invention, I declare that what I claim and desire to secure by Letters Patent, is:

1. The improved apparatus for locating lids on containers preparatorily to final closure, comprising:—a carrier member and an actuating member between which relative angular move-

ment can take place approximately about a central axis; means for producing such movement; means for locating the lids on the containers before clenching; a series of clenching members circumferentially spaced about the said axis and carried by the carrier member; each clenching member having a clenching face adapted when it is moved inwardly, to engage a section of the periphery of a lid on a container located in alignment with said axis and to clench the said section over the mouth of the container; means for connecting the clenching members to the carrier member which means constrain the movement of the clenching faces of the respective clenching members relatively to the carrier member, to a direction approximately radial to the said axis; and means connecting the clenching members to the actuating member and adapted, when there is relative angular movement between the carrier member and the actuating member to move said clenching faces inwardly to effect the clenching.

2. The combination with apparatus as claimed in claim 1, of means for holding the actuating member fixed against axial movement, means for holding the carrier member fixed against rotation, and means adapted, when the actuating member has angular movement imparted to it in one direction to move the carrier member and clenching members axially towards the positioned container and thereby cause the clenching members to press the lid onto the container as the clenching action takes place.

3. Apparatus according to claim 1 in which said means for locating the lids on the containers before clenching includes a magazine adapted to hold a stack of lids in alignment with the central axis, and means for releasing the lowermost lids of the stack in succession.

4. The combination with the apparatus claimed in claim 1, of;—means for holding the actuating member fixed against axial movement, means for holding the carrier member fixed against rotation, and means adapted, when the actuating member has angular movement imparted to it in one direction, to move the carrier member and clenching members axially towards the positioned container and thereby cause the clenching members to press the lid onto the container as the clenching action takes place; said means for locating the lids on the containers before clenching including a magazine adapted to hold a stack of lids in alignment with the central axis; and a series of supporting members carried by the carrier member and spaced between the clenching members, each supporting member having a lip adapted in one position of the member to engage the underside of the lowermost lid of the stack; means for connecting the supporting members to the carrier member which constrain the movement of the said lips, relatively to the carrier member, to a direction approximately radial to the central axis; and means connecting the supporting members to the actuating member adapted, when there is relative angular movement between the carrier member and the actuating member to effect the clenching to move said lips away from the lowermost lid of the stack; the clenching faces of the clenching members having inclined surfaces adapted, as the said lips leave the lowermost lid of the stack to engage the underside of the lid next to the lowermost lid, and support the stack of lids during the clenching movement.

5. In a machine for clenching lids on containers in combination:—an axially movable rotationally fixed carrier member; clenching members connected to the carrier member so that their clenching faces are constrained to move approximately radially relatively to the positioned container; supporting members connected to the carrier member so that their supporting lips are constrained to move approximately radially in relation to the positioned container; an actuating member capable of angular movements but held against axial movement; means for imparting angular movement to the actuating member; means by which angular movement of the actuating member is caused to impart said approximately radial movement to the said clenching faces and supporting lips, respectively, in opposite directions; means by which said angular movement of the actuating member imparts axial movement to the carrier member; a magazine adapted to hold a stack of superposed lids adapted to be supported by engagement with the lowermost lid of the said supporting lips, and before the latter releases said lid, by engagement with the succeeding lid of the clenching faces. 25

6. In apparatus for locating lids on containers preparatorily to final closure; in combination; a fixed bracket; a main flanged sleeve attached to the fixed bracket approximately concentrically with a central axis, said main flanged sleeve having a cylindrical portion, a carrier member comprising a flanged sleeve adapted to slide on the cylindrical portion of the main sleeve, but held against rotation thereon; an actuating member comprising a flanged sleeve mounted on the cylindrical portion of the carrier sleeve and rotatable thereon but fixed against axial movement; clenching members secured to the carrier member so that the clenching faces thereof are constrained to move approximately radially to the 40 said axis; supporting members secured to the carrier member so that the supporting lips thereof are constrained to move approximately radially to the said axis; studs attached to the clenching members and to the supporting members adapted 45 to pass through radial slots in the carrier member, and to engage in respective cam slots in the actuating member; said cam slots being respectively adapted, when angular movement is imparted to the actuating member in the one direction, to move the clenching faces of the clenching members towards the said axis and to move the said supporting lips of the supporting members away from the said axis, and vice-versa; a pin and cam slot connection between the actuating 50 ring and the carrier ring adapted, when angular motion is imparted to the actuating ring in the direction to effect clenching, to move the carrier ring and the clenching members towards the container with lid in position thereon and positioned 55 in alignment to the central axis, and thereby to press the lid into contact with the container as it is clenched thereon; a magazine adapted to hold a stack of lids in alignment with the positioned container so that the lowermost lid of the 60 stack is supported by the supporting members when the latter are in their innermost position, the clenching faces of the clenching members having inclined surfaces which as the supporting members are retracted are inserted between the 65 lowermost lid and the lid next above the lowermost lid and are adapted to support the stack of lids while the supporting members are disengaged therefrom.

7. A machine as claimed in claim 5 in which 75

the clenching members and supporting members are respectively slidably connected to the carrier member.

8. A machine as claimed in claim 5 in which 5 the clenching members and the supporting members are pivotally connected to the carrier member.

9. A machine as claimed in claim 5 in which 10 the respective connections between the clenching and supporting members and the actuating member comprise pins carried by the said members and respective cam slots formed in the actuating member.

10. A machine as claimed in claim 5 in which

the clenching faces of the clenching members have a horizontally disposed transverse recess to engage the section of the container lid to be clenched over, and a horizontally disposed latch-like projection adapted to enter between two adjacent lids in the magazine.

11. In a machine as claimed in claim 5, means 10 for imparting angular movement to the actuating member comprising a pivoted lever having at its free end a toothed section, and a corresponding toothed section formed on the actuating sleeve with which the teeth of the lever engage.

F. O. L. CHORLTON.
